RAILWAY SIGNAL CONTROL

Application filed February 25, 1931. Serial No. 518,167.

This invention relates to a car-operated circuit controller for railway crossing signals and other uses to which it may be applicable and is particularly useful in the automatic operation of more or less remote electrical or electro-mechanical signals through normally closed circuits.

The main object is to provide simple and efficient means whereby a car or train approaching a highway or other grade crossing from opposite directions will cause the operation of a suitable signal (preferably of the flash type) at or near the crossing and such operation to be continued until the car or train has passed said crossing and then to cause the signal and its operating means to be automatically restored to their normal starting conditions.

In other words I have sought to effect these operations through the medium of three somewhat similar track-instruments, one of which, to be known as a non-directional instrument, is installed along the track at or adjacent the crossing while the other two, to be known as directional instruments, are installed adjacent the track at more or less remote distances from and at opposite sides of the crossing so that one of the directional instruments and the non-directional instrument will be operated in sequence by the wheels of the car or train as the latter approaches and passes the crossing from either direction.

One of the specific objects is to provide each track instrument with a commutator mounted upon a crank-shaft which is operated directly by the wheels of the car for rocking the commutator from its normal position for opening the corresponding normally closed circuit.

Another specific object is to make the closing of the normally open signal circuit dependent upon the operation of the first instrument by the car and resultant opening of the corresponding normally closed circuit so that the two operations may take place simultaneously.

A further object is to cause the previously operated commutators of the directional and non-directional instruments to be automati-

cally restored to their normal positions as soon as the car or train passes those instruments.

Another object is to enable the commutator of the distant instrument to keep its circuit closed even though it may be operated by the car or train after passing the crossing.

Other objects and uses will be brought out in the following description.

In the drawings:

Figure 1 is a perspective view of portions of a railway track, partly broken away, showing diagrammatically a signal near the grade crossing, the non-directional track instrument at or adjacent the crossing and the directional track instruments located at opposite sides of the crossing some distance remote therefrom.

Figure 2 is an enlarged transverse vertical sectional view through one of the directional track instruments and adjacent portion of one of the rails taken in the plane of line 2-2, Figure 1.

Figures 3 and 4 are detail sectional views taken respectively in the planes of lines 3-3, 75 and 4-4, Figure 2.

Figure 5 is a horizontal detail sectional view taken in the plane of line 5-5, Figure 4.

Figures 6 and 7 are enlarged detail end views, partly in section, of portions of the non-directional instrument and one of the directional instruments showing their respective commutators in their normal positions.

Figure 8 is a diagrammatic view of the car-operated commutators of the several track instruments together with the correlated electric circuits for controlling the operation of the crossing signal indicated in Figure 1.

In order that the invention may be clearly understood I have shown portions of a single railway track —A— extending some distance beyond opposite sides of a highway grade crossing as —B—, shown by dotted lines in Figure 1. A suitable signal —C— is also permanently installed adjacent the intersection of the track —A— and grade crossing —B—, said signal being shown dia-

grammatically in Figure 8 as consisting of an electric gong.

A non-directional track instrument —D— is also installed adjacent one of the rails 5 of the track near its intersection with the grade crossing —B— or normally adjacent the signal —C— to be operated by a car or train moving along the track.

Similar directional track instruments 10 —E— and —E'— are installed adjacent one of the rails of the track at distances more or less remote from and at opposite sides of the grade crossing —B—, and preferably at corresponding distances from the signal 15 —C— and non-directional track instrument —D—.

These three track instruments are quite similar in their construction and operation in that they are provided respectively with 20 commutators —d—, —e— and —e'— and cooperative pairs of contacts —f—, —g— and —g'—, the commutators being mounted upon separate rock shafts —h—, —i— and —i'— having crank arms —j—, —k— and —k'—, as shown more clearly in Figure 8; the latter being provided respectively with rollers —m—, —n— and —n'— normally projecting into the path of the flange or tread of the wheels of the car or train moving along 25 the track for rocking the corresponding arms —j—, —k— and —k'— and their respective commutators —d—, —e— and —e'— from their normal positions, shown in Figure 8.

The contact brushes —f—, —g— and —g'— for each of the commutators are located at diametrically opposite sides thereof, the commutator —d— being provided with a peripheral segment —o— which, in this instance, is somewhat less than a half 35 circle and is normally in a position between and out of contact with the corresponding contact brushes —f— so that the circuit in which the brushes —f— are connected will be normally broken or open.

40 The commutator —e— is provided with a peripheral segment —s— of greater circumferential length than a half circle and normally in contact with both of the brushes —g— to close the circuit in which said brushes are connected.

In like manner the commutator —e'— is provided with a peripheral segment —s'— of greater circumferential length than a half circle to normally contact with both of the brushes —g'—, and thereby to close the circuit in which the brushes are connected.

45 The several commutators —d—, —e— and —e'— are of substantially the same diameter and disposed in substantially the same horizontal plane along one of the rails of the track —A— and are secured to their respective rock shafts —h—, —i— and —i'— to rotate therewith, the crank arms —j—, —k— and —k'— being of substantially equal 50 radial length and normally disposed in ver-

tical positions with their contact rollers —m—, —n— and —n'— in the path of the flanges of the car-wheels to be engaged thereby for rocking the shafts and commutators through an arc of approximately ninety degrees, more or less, as the car or train is moving in either direction along the track. 70

As previously stated the conducting segment —o— of the commutator —d— is normally arranged at the lower side of the commutator between and out of contact with both of the brushes —f— but is adapted to engage one of the brushes when actuated by the car to close the circuit through said contacting brush while breaking the circuit through the other contacting brush for a purpose herein-after described. 75

The conducting segment —s— of the commutator —e— is normally in contact with both of the brushes —g— for closing the circuit in which the brushes are connected and extend through an arc of slightly more than three-quarters of the circle leaving an insulating space between its ends. 80

The end of the segment —s— facing the non-directional instrument —D— is normally only a short distance (considerably less than ninety degrees) from its point of contact with the corresponding brush —g— so that when the commutator —e— is rocked by a train or car moving in the direction of the grade crossing, the end of the segment facing the crossing will be moved out of contact with the corresponding brush —g— for breaking or opening the local circuit while the opposite end of the same segment will maintain contact with the corresponding brush —g— for a purpose hereinafter more fully described. 85

In reverse manner, the end of the segment —s'— facing the crossing will be a relatively short distance (considerably less than ninety degrees) from its point of contact with the corresponding brush —g'— so that when the train is approaching the crossing from the side at which the instrument —E'— is located, the engagement of the car-wheel with the contact member —n'— will rock the commutator toward the crossing and thereby move the segment —s'— out of contact with the inner brush —g'— for breaking the local circuit, while the other end of the segment will still maintain contact with the outer brush —g'— for a purpose hereinafter described. 90

Both of the segments —s— and —s'— are of sufficient circumferential length to maintain contact with both of the brushes when moved outwardly or in directions away from the crossing for the purpose of keeping the local circuits closed for a purpose hereinafter explained. 105

The commutators —e— and —e'— and their brushes —g— and —g'— are substantially identical except that the segments —s— 110

and —*s'*— are reversed in their direction of extension around their respective supporting drums which are preferably made of insulating material, while the segment of the commutator —*d*— is electrically connected to the rock shaft —*h*— through the medium of a metallic conductor —*d'*—, shown by dotted lines in Figure 8.

Aside from these structural differences the 10 three track instruments —*d*—, —*e*— and —*e'*— are substantially identical in that each comprises a housing —1— arranged along the inner side of one of the rails —*a*— of the track —*A*— and rigidly clamped thereto by 15 means of clamping bolts —2— and clamping heads —3—.

The adjacent edges of the housing —1— and clamping head —3— are provided with grooves —4— and —4'— for receiving and 20 engaging the inner and outer edges of the base flange of the rail, as shown more clearly in Figure 2, the bolts —2— being passed through registering apertures in the lower sides of the housing —1— and clamping 25 member —3— and provided at one end with nuts —2'— for tightening and releasing the members —1— and —3— upon and from the flange of the rail. See Figures 2 and 4.

The rock shaft of each track instrument 30 preferably extends transversely of and across the interior of the corresponding housing —1— and is journaled in suitable bearings —5— in opposite sides of the housing, as shown more clearly in Figure 2, for receiving 35 and supporting the adjacent commutator within the housing, said rock shaft being extended outwardly beyond the adjacent portion of the housing toward the rail —*a*— for receiving and supporting the corresponding 40 crank arm as —*k*— between said housing and rail, as shown in Figure 2, it being understood that the crank arm —*k*— is splined or otherwise secured to the adjacent end of the rock shaft as —*i*— for rotating the same 45 when actuated by the car-wheel.

Each commutator as —*e*— is preferably composed of two cylindrical drum sections as —*e''*— splined or otherwise secured to the corresponding rock shaft to rotate therewith 50 within the housing —1— and preferably arranged in axially spaced relation for receiving between them an additional crank arm —6— which is also splined or otherwise secured to the rock shaft to rotate therewith. 55 Each of the crank arms —6— is normally disposed in a vertical plane parallel with, and extending the same direction from the rock shaft as the crank arm —*k*— and has its upper end provided with a vertically elongated slot —7— open at the top for receiving a pair of oppositely extending piston rods —8— and —9—, the adjacent ends of which overlap each other and are provided with lengthwise slots —10— and —11— for 60 receiving a cross-pin —12— on the crank 65

arm —6— and establishing a pin and slot connection between the crank arm and piston rods, as shown more clearly in Figures 2 and 4.

These piston rods —8— and —9— extend horizontally in opposite directions from the pivotal pin —12— and are provided at their outer ends with pistons —13— and —14— respectively, said pistons being movable in corresponding cylinders —15— and —16— 75 against the action of suitable coil springs —17— and —18—, as shown more clearly in Figure 4.

These cylinders —17— and —18— have 80 their outer ends pivoted at —19— and —20— respectively to the adjacent end walls of the housing —1— to permit them to rock vertically about said pivots and thereby to compensate for varying vertical positions of the piston rods —8— and —9— as the latter are 85 reciprocated endwise by the crank arm —6—.

The length of each slot —10— and —11— is approximately equal to the length of the 90 arc through which the pivotal pin —12— on the crank arm —6— is movable from its normal position in either direction, but the end walls of the slots of both piston rods are normally held in engagement with the pivotal pin —12— by the expanding action of 95 the corresponding springs —17— and —18— when the crank arm —6— is in its normal position, as shown in Figure 4, each cylinder being provided with an air vent —21— to avoid trapping of the air in the outer 100 ends thereof as the pistons are moved outwardly or toward the pivotal ends of the cylinders, and retard the return of the pistons.

It is now clear that if the crank arms of any one of the instruments is rocked in one direction as, for example, in the direction indicated by the arrow —*x*—, Figure 4, the pin —12— will force the rod —8— endwise into the cylinder —15— against the action of the corresponding spring —17—, thereby 105 effecting a corresponding rotary movement of the adjacent commutator as —*e*—, while at the same time the pin —12— will be free to slide endwise in the slot —11— of the other piston rod —9—.

On the other hand if the crank arm of any one of the instruments is moved in the opposite direction from its normal position the pin —12— will effect a corresponding endwise movement of the piston rod —9— and its piston —14— against the action of the corresponding spring —18— in which case the pin —12— will simply slide endwise in the slot —10— of the piston rod —8—.

Immediately following the operation of 115 the crank arms and commutator of any one of the instruments from its normal position by a moving car or train, the piston rod actuated thereby will be restored to its normal position by the corresponding spring as —17— or —18— for a purpose presently de- 120 125 130

scribed in connection with the several circuits and electrical devices controlled by the movements of the commutators.

For example, assuming that the commutators and their crank arms are in their normal positions as would be the case when no train is present at either one of the track instruments, under which conditions the segment —*s*— of the track instrument —*E*— 10 would be in contact with both of the brushes —*g*—.

These brushes are connected in an electric circuit deriving current from the source of energy —*T*—, said circuit including therein 15 a relay or electro-magnet —22— and a switch member —23— which is normally in contact with a contact member —24—, thus constituting a normally closed circuit in which the current from the source —*T*— may pass 20 from said source through the wires —25— and —26—, through brushes —*g*— and segment —*s*—, and thence through wires —27— to and through the electro-magnet —22— and switch members —23— and —24— to return 25 through wires —28— to the source of electric energy —*T*—, thus completing a normally closed circuit.

Now, as soon as the train approaches the track instrument —*E*—, it will operate the 30 commutator —*e*— in the direction indicated by arrow —*y*—, Figure 8, to break the electrical connection between the segment —*s*— and right hand brush —*g*— while maintaining contact between the segment —*s*— and lefthand brush —*g*—, thereby breaking the 35 normally closed circuit through the electro-magnet —22— and switch members —23— and —24— and allowing said switch members to open.

20 The switch member —23— is electrically and mechanically connected by means of a bar —29— to additional switch members —30— and —31—, one of which, as —30—, is normally in contact with a companion 25 switch member —32— and, when opened is arranged to contact with another switch member —32'— while the switch member —31— is normally open, but adapted to contact with a companion member —31'—, said 30 switch members —23—, —30— and —31— being pivoted respectively at —33—, —34— and —35— to suitable supports, not shown.

When the normal closed circuit, previously 35 described, is opened by the operation of the commutator —*e*—, the resultant deenergizing of the electro-magnet —22— will allow the switch member —23— to open, and the switch member —30— to close contact with the member —32'—, while at the same time the switch 40 member —31— will be allowed to contact with its companion member —31'—.

Under these conditions the current from the 45 source —*T*— will be diverted from the wire —25— through another wire —36— and thence to the switch members —30— and —32'—

and thence through wires —37— to the signal —*C*— for operating the latter immediately upon the breaking of the normally closed circuit, previously explained, and resultant closing of the switch member —30— upon its 50 companion member —32'—, the current then returning from the signal through wire —38— to the source —*T*—.

The operation of the signal will thus continue as long as the car or train is passing and holding the commutator —*e*— against returning and also while the car or train is passing from the instrument —*E*— to the instrument —*D*—.

That is, as soon as the train passes the instrument —*D*— and releases the commutator —*e*—, it will be returned to its normal position by the corresponding spring —17—, as shown in Figure 4, but owing to the fact that the switch member —23— has been previously opened it will break the normally closed circuit in which the relay —22— is connected, thereby preventing the energizing of said relay, at which time the switch members —30— and —32— and —31— and —31'— will remain in contact for continuing the operation of the signal —*C*— while the car or train is in transit from instrument —*E*— to instrument —*D*—.

Now as the car or train continues to move 55 toward the track instrument —*D*— it will engage and operate the crank arm —*j*— for rotating the commutator —*d*— in the direction indicated by arrow —*x'*—, Figure 8, thereby bringing the segment —*o*— of said 100 commutator into contact with the lefthand brush —*f*— while still out of contact with the right hand brush —*f*—.

It will be remembered that at this time the switch member —31— will be in contact with the companion member —31'— and that the segment —*s*— will be in contact with both of the brushes —*g*— so that when the segment —*o*— is in contact with the lefthand brush —*f*— of the instrument —*D*—, the current from the source —*T*— will pass through wires —25— and —26—, brushes —*g*—, and segment —*s*—, and thence through additional wire —39— and an electro magnet —40— from which it passes through the then closed switch members —31— and —31'— and thence through wires —41— and —42— to the lefthand brush —*f*—, thence through the conductor —*d'*— of the commutator —*d*— to the shaft —*h*— and on through additional wires —43— and —44— to the signal —*C*— to return to the source —*T*— through wire —28—.

It will be noted that, immediately upon the 125 energizing of the relay —40— to open the switch member —31—, the switch member —23— will be closed thereby again closing the local circuit of the instrument —*E*— through the relay —22— for holding the switch members —23— and —30— closed on 130

their respective contacts —24— and —32— and also holding the switch member —31— in its open position.

Under these conditions the operation of the signal —D— will be continued until the car or train passes the instrument —D—, whereupon the commutator —d— will be restored to its normal position by the spring —17— of the corresponding instrument with the segment —o— out of contact with both of the brushes —f— for breaking the signal circuit and stopping the operation of the signal.

The commutators of the instruments —D—, —E— and —E'— are now restored to their normal positions as shown in Figure 8, with the signal —C— at rest ready for a repetition of the operations described by another car or train moving in the same direction or in an opposite direction from that indicated by the arrows.

That is, a train approaching the crossing from the right hand of Figure 8 will successively operate the commutators —e'— and —d— in the same direction to produce the same effects upon the signal —C— as previously described, and for this purpose I have shown duplicate relays —22'— and —40'— and duplicate switch members —23'—, —30'— and —31''— with their cooperative contacts all connected to the brushes —g'— of the commutator —E'— and to the signal circuit in a manner similar to that previously explained.

For example, when no car or train is approaching the crossing from the right hand of Figure 8 of the segment —S'— of instrument —E'— will be in contact with both of the brushes —g'—, thus closing the circuit from the generator —T—, through wires —25'—, —26'—, brushes —g'— and segment —s'—, thence through wires —27'—, relay —22'—, switch member —23'— and return through wire —28'— to the source —T—.

Then when the commutator is shifted by the car moving in a direction opposite that indicated by the arrows, Figure 8, the previously closed local circuit will be broken, thereby de-energizing the relay —22'— and allowing the switch member —23'— to open and the switch member —31''— to close and at the same time allowing the switch member —30'— to open from its upper contact and close upon its lower contact for diverting the current from the wire —26'— through the wire —44— and signal —C— to operate said signal.

This operation of the signal will continue while the car or train is in transit from instrument —E'— to instrument —D— at the crossing —B— at which time the train will have passed instrument —E— to allow its commutator to be restored to its normal position by its spring —17— for again closing the local circuit.

The continued movement of the car or train from the right hand toward the left hand of

Figure 8 will cause the operation of the commutator —d— in the same direction thereby bringing its segment —o— into contact with the right hand brush —f— so that the current will then be temporarily diverted from the line —25'—, through line —26'—, brushes —g'— and segment —s'—, relay —40'— and the then closed switch member —31''—, and thence through line —41'— to the right hand brush —f—, through segment —o— to shaft —h—, through lines —43— and —44— to signal —C— for operating the latter.

Immediately upon the energizing of the relay —40'— the switch members —23'—, —30'— and —31''— will be restored to their normal starting positions thereby diverting the current from line —25'— through line —36'—, switch member —30'— to right hand brush —f—, thence through segment —o—, shaft —h— and line —43— to the signal —C— for continuing the operation of said signal while the car or train is passing the crossing —B—, and at the same time the closing of the switch member —23'— will again close the local circuit through the instrument —E'—.

As soon as the car or train has passed the instrument —D— and adjacent crossing, the commutator —d— will be restored to its normal position for breaking the circuit through and stopping the operation of the signal —C—.

It will be observed that after a car or train, moving in either direction, has passed the crossing —B— and adjacent instrument —D— it will engage and operate the distant commutator in the same direction and that these operations will have no effect whatever upon the signal —C— by reason of the fact that the segments —s— and —s'— are sufficiently long to maintain contact with their respective brushes —g— and —g'— during such operations.

It is believed that the construction and operation have been described in such full clear and exact terms as to enable anyone skilled in the art to make and use the same but obviously various changes may be made in the detail construction without departing from the spirit of such invention.

What I claim is:—

1. In a track equipment of the character described, a normally closed circuit controller adapted to be actuated by a moving car for opening the same, a second normally open circuit controller located some distance from the first controller in the direction of movement of the car and adapted to be actuated by the car for closing the same, a normally de-energized signal circuit, means brought into action by the opening of the first-named controller for causing the energizing of the signal circuit, and means brought into action by the closing of the second-named controller for continuing the signal circuit.

energizing of the signal circuit after the car has passed the first-named controller.

2. In a track equipment of the character described, a normally closed circuit controller adapted to be actuated by a moving car for opening the same, a second normally open circuit controller located some distance from the first controller in the direction of movement of the car and adapted to be actuated by the car for closing the same, a normally de-energized signal circuit, means brought into action by the opening of the first-named controller for causing the energizing of the signal circuit, and means brought into action by the closing of the second-named controller for continuing the energizing of the signal circuit after the car has passed the first-named controller, said first-named controller being operable by a car moving in the opposite direction and having means for maintaining its closed position when so operated.

3. In a track equipment of the character described, a circuit controller including a contact brush and a commutator segment movable about an axis into and out of contact with the brush and normally in contact with said brush for closing said circuit, means actuated by a car moving along the track for moving the segment out of contact with the brush to break said circuit, a normally open signal circuit, and means brought into action by the breaking of the first-named circuit for closing the signal circuit.

4. In a track equipment of the character described, a circuit controller including a contact brush and a commutator segment movable about an axis into and out of contact with the brush, and normally in contact with said brush for closing said circuit, means actuated by a car moving along the track for moving the segment out of contact with the brush to break said circuit, a normally open signal circuit, means brought into action by the breaking of the first-named circuit for closing the signal circuit, and means actuated by the moving car after passing said controller for re-closing the first-named circuit and for closing the signal circuit.

5. In a track equipment of the character described, a normally open signal circuit, a circuit controller including a brush and a commutator segment normally in contact with the brush and movable about an axis, car-actuated means for moving said segment out of contact with the brush, and means brought into action by the breaking of said contact for closing the signal circuit.

6. In a track equipment of the character described, a normally open circuit closer adapted to be closed by a car moving in either direction, additional normally closed circuit controllers located at opposite sides of the first-named circuit closer and adapted to be opened by the car moving toward said first-

named circuit closer, said additional circuit closers having means for maintaining their closed position when operated by a car moving in a direction away from the first-named circuit closer, a normally open signal circuit, means brought into action by the opening of either of the additional circuit closers for closing the signal circuit, means brought into action by the closing of the first-named circuit closer for continuing the closing of said signal circuit, and separate devices for restoring the circuit closers to their normal positions after the car has passed the first-named circuit closer.

7. In a track instrument of the character described, a circuit controller comprising a rock-shaft having axially spaced crank-arms, one of which is adapted to be engaged and operated from a normal position by a car or train moving along the track in either direction, a switch member mounted on said shaft to rotate therewith for opening and closing said circuit, a support for the rock-shaft, dash-pots mounted on the support at opposite sides of the rock-shaft, separate devices for transmitting motion from the other crank-arm to the pistons of their respective dash-pots, and separate springs, one for each dash-pot and each acting upon its corresponding piston and transmitting devices for restoring the rock-shaft and parts carried thereby to their normal positions.

In witness whereof I have hereunto set my hand this 19th day of February, 1931.

WILLIAM R. BURKE.
